UNITED STATES PATENT OFFICE.

FRANZ TRINKS, OF BRUNSWICK, GERMANY.

CALCULATING-MACHINE.

1,220,030.

specification of Letters Patent. Patented Mar. 20, 1917.

Application filed June 12, 1916. Serial No. 102,524.

To all whom it may concern:

Be it known that I, FRANZ TRINKS, manufacturer, citizen of the Duchy of Brunswick, Empire of Germany, residing at 5 Brunswick, Germany, have invented certain new and useful Improvements in Calculating-Machines, of which the following is a specification.

My present invention relates to calculating machines, and in particular to calculating machines of the character described and illustrated in my United States Patent No. 1,040,050, dated October 1, 1912. My invention relates more especially to a device 15 for restoring to the initial or zero position, the handles which serve for setting up numbers and items in the machine.

It is the object of my present invention to provide means which are actuated by the 20 main operating member of the machine and which cause the setting up handles to assume their initial or zero position prior to the conclusion of the movement of the main operating member.

25 A further object of my present invention is to provide means for interrupting the operative connection of the main operating member with the first named means for restoring the setting up handles to their initial or zero position.

A still further object of my present invention is to provide in conjunction with the last named means special means by 35 which the member that directly acts upon the said handles to assume their initial or zero position is enabled to automatically move into a third or neutral position; and a provision is made for simultaneously locking said member in the third or neutral 40 position.

With these and other objects in view, my present invention resides in the provision of an operative connection between the main operating member of the machine and a 45 blocking member adapted to be moved into, and out of, the path of movement of the setting up handles, whereby said blocking member is rendered operative on actuation of the main operating member, and is rendered inoperative prior to the conclusion of the actuating movement of the main operating member. In conjunction therewith a hand operated mechanism is provided by 50 means of which the said operative connection between the blocking member and the main operating member can be interrupted

at will and the blocking member caused to move into and out of a third or neutral position in which the same is simultaneously locked.

60 I have illustrated an embodiment of my invention in the accompanying drawings by way of example: Figure 1 is a fragmentary side view of a machine of the character for which my present invention is especially applicable; the casing being partly removed to show one of the revolvable setting up disks with the setting-up handle attached thereto. Fig. 2 is a front elevation, partly in section. Fig. 3 is a fragmentary plan view. Fig. 4 is a side view, similar to Fig. 1, of one of the revolvable setting-up disks, with the blocking member in operative position. Fig. 5 is a fragmentary sectional front view, similar to Fig. 2, with the blocking member in operative position. Fig. 6 is a view similar to Fig. 3, with the blocking member, indicated in dotted lines, in its operative position. Fig. 7 showing a cam as applied in connection with the novel mechanism. Fig. 8 is a view similar to Fig. 5 with some of the operative parts in another relative position. In Figs. 9 to 12 are shown modified constructions for carrying my invention into effect.

85 Referring to the drawings, *a* designates slots provided in the casing of the machine and allowing the setting-up handles *b* to protrude from the casing. Fig. 1 shows the initial or zero position of the handle *b*, and 90 the arrow indicates the direction in which the setting-up disk with the handle *b* attached therewith, revolves when actuated by means of the main operating member, for setting up numbers and items in the machine. Beneath the upper ends of the slots *a* is provided a slide *c* having tooth-like projections *d* which correspond in number and division to the bridges *e* intermediate and forming said slots *a* in the casing. The 95 projections *d*, in the normal position of the slide, lie beneath the said bridges, as shown in Figs. 1, 2, 3; when the slide *c* is moved lengthwise, the projections will then block the slots *a* in the manner shown in Figs. 4, 100 5, and 6. With the blocking slide *c* in the latter position, the handles *b* will be prevented from entering the slots *a* while the setting disk is revolving. By being withheld from entering the slots *a* while the 105 actuating shaft *b* is moving on, the handles, and the parts associated therewith, are re-

stored to the initial or zero position. When all of the handles *b* are thus restored to zero position, the blocking slide *c* is automatically shifted from its operative position, shown in Fig. 5, to its inoperative position, shown in Fig. 2. This shifting takes place prior to the conclusion of the movement of the main operating handle *w* actuating the shaft *f* on which the setting disks with the handles *b* are mounted.

Through my present invention the automatic shifting of the blocking slide *c* is carried out in the following manner. The setting shaft *f* carries a fixed cam disk *g* (Figs. 2, 5, 7, 8) which, in timed intervals, actuates a lever *h* (Fig. 7) which is provided with a beveled side *h'* adapted to engage a correspondingly beveled depending head *i* of the blocking slide *c*. When the lever *h* is being raised by the cam *g*, the blocking slide *c* will be pushed back lengthwise into the position, shown in Fig. 5, and against the resistance of the spring *k* connected with the slide *c* to retain the same in its inoperative position. The cam *g* is timed so as to permit the lever *h* to swing downward as soon as all of the setting-up handles *b* are restored to zero. The spring *k*, then, acts to press the blocking slide *c* again into the inoperative position shown in Fig. 2.

A stop *l* is provided to limit the movement caused under the action of the spring *k*. However, the stop *l* is not stationary, but can be caused to swing out of touch with the blocking slide *c*, through the agency of the handle *m* provided without the machine casing. The blocking slide *c*, is, then, able to travel farther to the left, to the position shown in Fig. 8. With the shaft of the handle *m*, is positively connected a pin *n* which engages the lever *h* when the handle *m* is being actuated and lifts the same out of the control of the cam *g*. Thus raised, the lever *h* comes into position to the right of the head *i* and thereby locks the latter against accidental displacement. The stop *l* is furnished with a beveled side face which engages the head *i* and pushes the same back into the inoperative position shown in Fig. 2 when the handle *m* is returned. Previously to the shift of the blocking slide *c* the pin *n* permits the lever *h* to drop.

Hence, through manipulation of the handle *m* the automatically acting mechanism for restoring the setting handles *b* to zero position, can be rendered operative and inoperative at will.

Instead of performing a lengthwise shifting movement, the blocking slide can just as well be adapted to perform a crosswise directed swinging movement. The alterations required for such a modified construction are simple in nature and can be readily inferred from the view reproduced in Fig. 12. For this purpose, the blocking slide

need not be furnished with teeth *d*, but may consist of a straight bar.

There are calculating machines in which the setting-up handles do not participate in the revolving movement of the actuating member but are previously dissociated from the operative setting-up mechanism (comprising grooved cam disks). Such a machine is for instance described in my United States Patent No. 843,503, dated February 2, 1907. In a machine of this type, my present invention may just as well be applied for restoring the setting-up members to zero position; it is only required to provide projections on the revolving setting-up members so as to coact with the blocking slide in the same manner as the revolving setting-up handles *b* described hereinbefore. The handles which have previously been dissociated from the setting-up members, are then separately restored to zero position which may be readily accomplished in any suitable manner. The slight modifications required, may be readily understood from the following example. The setting shaft *f* in Fig. 9 carries a loosely supported handle *b'* attached to a toothed disk *p* which meshes with a pinion *o* fixedly mounted on a restoring shaft *q*, which is well known as regards its function. The shaft *q* is equipped with a screw threaded face by which the revolving shaft is caused to move longitudinally. Thereby, radially disposed pins of the shaft *q* engage axially projecting pins of the pinions *o* and thus compel the latter to participate in the revolution of the shaft *q* (Fig. 10). The revolving movement of the shaft *q* may be transmitted to the latter from the main actuating member of the machine by means of a toothed sector *r* (Fig. 11) mounted so on the shaft *f* as to engage, during the last part of the movement of the main actuating member, a pinion *s* fixedly mounted on the shaft *q*. One of the two parts, *s* or *r*, must be given a sufficient width to allow of a longitudinal displacement of the shaft *q* without thereby disengaging the pinion *s* from the gear wheel *r*.

Other possible modifications within the scope of my invention will readily occur to those skilled in the art to which my invention appertains.

What I claim as my invention and desire to secure by Letters Patent of the United States, is:

1. In a calculating machine, in combination with a main operating member, and a mechanism comprising setting handles for setting up numbers and items, a slidable blocking member for said handles, and an operative connection between said main operating member and said blocking member, whereby said blocking member is automatically rendered operative on actuation of said main operating member and is rendered in-

operative prior to the conclusion of the movement of said main operating member.

2. In a calculating machine, in combination with the main operating member and a mechanism comprising setting handles for setting up numbers and items, a slidable blocking member for said handles, a cam positively connected with said main operating member, a movable member adapted to be actuated by said cam and engaging said blocking member so as to reciprocate the same between its inoperative and its operative positions when said movable member is correspondingly actuated by said cam, whereby said blocking member is automatically rendered operative on actuation of said main operating member and is rendered inoperative prior to the conclusion of the movement of said main operating member, 75

15 whereby said blocking member is automatically rendered operative on actuation of said

main operating member and is rendered inoperative prior to the conclusion of the movement of said main operating member.

20 3. In a calculating machine, in combination with a main operating member and a mechanism comprising setting handles for setting up numbers and items, a slidable blocking member for said handles, yielding means on said blocking member and tending to retain said blocking member in its inoperative position, a shaft carrying said setting mechanism and having a driving connection with said main operating member, a 25 cam on said shaft, a pivotally mounted lever adapted to be swung by said cam, an operative engagement between said lever and said blocking member, enabling said lever to cause a longitudinal displacement of said blocking member, whereby said blocking member is automatically rendered operative on actuation of said main operating member and is permitted to resume the inoperative position under the action of said yielding means and 30 prior to the conclusion of the movement of said main operating member, and a stop adapted to limit the return movement of said blocking member.

4. In a calculating machine, in combination with a main operating member, and a mechanism comprising setting handles for setting up numbers and items, a slidable blocking member for said handles, an operative connection between said main operating member and said blocking member, whereby said blocking member is automatically rendered operative on actuation of said main operating member and is rendered inoperative prior to the conclusion of the movement 45 of said main operating member, and means enabling the operator to disconnect the said operative connection between said main operating member and said blocking member.

5. In a calculating machine, in combination with the main operating member and a mechanism comprising setting handles for setting up numbers and items, a slidable blocking member for said handles, a cam positively connected with said main operating member, a movable member adapted to

be actuated by said cam and engaging said blocking member so as to reciprocate the same between its inoperative and its operative positions when said movable member is correspondingly actuated by said cam, 70 whereby said blocking member is automatically rendered operative on actuation of said main operating member and is rendered inoperative prior to the conclusion of the movement of said main operating member, 75 and a revoluble member enabling the operator to disengage said movable member and said cam actuating said movable member, for the purpose of interrupting the operative connection between said main operating member and said blocking member.

6. In a calculating machine, in combination with a main operating member and a mechanism comprising setting handles for setting up numbers and items, a slidable 85 blocking member for said handles, a spring acting on said blocking member in one direction, a cam positively connected with said main operating member, a pivotally mounted lever adapted to be swung by said cam, an operative engagement between said lever and said blocking member and enabling said lever to cause a longitudinal displacement of said blocking member and against the action of said spring, whereby 90 said blocking member is automatically rendered operative on actuation of said main operating member and is permitted to resume the inoperative position under the action of said spring and prior to the conclusion of the movement of said main operating member, a stop adapted to limit the return movement of said blocking member to its inoperative position, a revoluble member adapted to raise said lever out of engagement with said cam and enabling the operator to interrupt the operative connection between said main operating member 100 and said blocking member, and a connection between said stop and said revoluble member, whereby said stop is swung out of the path of said blocking member on actuation of said revoluble member, whereupon said blocking member is permitted to move to a third position and sufficiently past said 105 pivotally mounted lever that the latter acts as a non-return stop to said blocking member on being raised by said revoluble member.

7. In a calculating machine, in combination with a main operating member and a mechanism comprising setting handles for setting up numbers and items, a slidable blocking member for said handles, a spring acting on said blocking member in one direction, a cam positively connected with said main operating member, a pivotally mounted lever adapted to be swung by said cam, an operative engagement between said lever and said blocking member and en- 110

115

130

abling said lever to cause a longitudinal displacement of said blocking member and against the action of said spring, whereby said blocking member is automatically rendered operative on actuation of said main operating member and is permitted to resume the inoperative position under the action of said spring and prior to the conclusion of the movement of said main operating member, a stop adapted to limit the return movement of said blocking member to its inoperative position, a revoluble member adapted to raise said lever out of engagement with said cam and enabling the operator to interrupt the operative connection between said main operating member and said blocking member, and a connection between said stop and said revoluble member, whereby said stop is swung out of the path of said blocking member on actuation of said revoluble member, whereupon said

blocking member is permitted to move to a third position and sufficiently past said pivotally mounted lever that the latter acts as a non-return stop to said blocking member 25 on being raised by said revoluble member, and a beveled face on said stop and adapted to engage said blocking member and return same from the said third position to the inoperative position when said revoluble 30 member is returned into its initial position for the purpose of restoring the operative connection between said blocking member and said main operating member.

In testimony whereof I have hereunto set 35 my hand in presence of two subscribing witnesses.

FRANZ TRINKS.
